REFRIGERATING APPARATUS

Richard W. Kritzer, Chicago, Ill.

Application January 13, 1956, Serial No. 558,891

8 Claims. (Cl. 62—196)

The invention relates to refrigerating apparatus of the type in which the condenser for the refrigerant is subjected to outside air and a cooling unit or evaporator is disposed inside of the building.

In apparatus of this type, unusually low temperatures during cold weather sometimes cause the refrigerant to be sucked from the evaporator into the condenser. This reduces the flow to the compressor and prevents circulation of the refrigerant through the evaporator for adequate cooling.

One object of the invention is to provide equipment which will insure circulation of the refrigerant during severe temperature-drops in the condenser when it is subjected to outside air.

Another object of the invention is to provide means for boosting the pressure of the refrigerant in the condenser to reduce the load on the compressor and to economize in the consumption of power.

Other objects of the invention will appear from the detail description.

The invention consists in the several novel features hereinafter set forth and more particularly defined by claims at the conclusion hereof.

In the drawings:

Fig. 1 is a vertical section, parts being shown in elevation, of refrigerating and cooling apparatus embodying the invention; and

Fig. 2 is a diagrammatic view of the electrical circuits for the compressor-motor, the valve for by-passing the refrigerant around the compressor, and the valve for closing the conduit between the refrigerant-pump and the condenser-coils.

The invention is exemplified in apparatus which comprises: a refrigerating unit which is mounted on the roof or outside of a building and includes a compressor, a liquid-receiver and a condenser; and an air cooling or conditioning unit which is mounted inside of the building and includes an evaporator and an air impeller. As the result of this disposition of these units outside and inside of the building during different seasons of the year, the refrigerant in the condenser is subjected to wide changes of temperatures relatively to the temperature of the refrigerant in the evaporator. For example, the cooling temperature of refrigerant in the evaporator may range from 32° to 40° F. with a pressure of 30 to 40 lbs. p.s.i., while as the result of a temperature drop caused by weather changes, for example to 24° F., the temperature of the refrigerant in the condenser-coils will drop below the temperature in the evaporator so that the refrigerant in the evaporator will be sucked into the condenser which renders the compressor ineffective to adequately circulate the refrigerant through the evaporator for the desired cooling. The present invention includes a pump for continuing the feed of refrigerant to the evaporator notwithstanding the changes in pressure in the refrigerant in the condenser-coils from weather conditions in connection with a by-pass conduit for the refrigerant around

2

the compressor and from the evaporator to the condenser-coils and also for utilizing the pump to economize the work of the compressor.

The invention is exemplified in refrigerating apparatus which comprises: a combined electric-motor and compressor unit 20 for the refrigerant; a condenser including heat exchange coils 21 and an air impeller 22 driven by an electric-motor 23, all disposed in a suitable casing or housing 24 mounted on the roof 25 of a building where outside air is available; and a cooling unit which is disposed inside of the building and comprises: an evaporator 26 including finned coils and an air impeller 27 driven by an electric-motor 28 and are all mounted in a casing or housing 29 disposed inside of the building. The impeller is supported in a frame 29a in casing 29. The casing 24 is secured on a plate 30 which fits over a curb 31 around an opening 33 in the roof 25 and has affixed thereto a pendant section of tubing 34. The casing 29 is secured to an upstanding tube-section 35 which fits telescopically in the tube 34 and is adjustably secured therein by one or more set-screws 36. The high pressure side of the compressor is connected by a conduit 40 to the inlet-header 41 for the condenser coils 21. The outlet-header 42 for coils 21 is connected by a conduit 43 to deliver refrigerant into the liquid-receiver 44. The low pressure side of the compressor of unit 20 is connected by a conduit 45 to the outlet-header 46 of the coils of evaporator 26. The inlet-header 47 for the coils of evaporator 26 is connected by a conduit 48 to the outlet side of a rotary pump 50 which has its inlet side connected by a conduit 51 to the bottom of the receiver. An expansion valve 49 is included in conduit 48. Rotary pump 50 is driven by a pulley 52 on the shaft of motor 23, a pulley 53 on the shaft of said pump and a V-belt 54 between said pulleys. Pump 50 has its intake conduit 51 leading from the bottom of receiver 44 and its discharge side is connected to conduit 48 which is connected to the inlet-header 47 of the evaporator-coil. A conduit 59 between the discharge side of pump 50 and the inlet-header 41 of the condenser includes a thermostatically controlled valve 58 which, when open, permits pump 50 to force via conduit 59 some of the refrigerant from receiver 44 into the inlet-header 41 for the coils of the condenser 21. When valve 72 is open and pump 50 and the compressor are both operated, the pressures of refrigerant forced by pump 50 and by the compressor into the inlet header 41 are cumulative in the condenser. When valve 58 is closed and the compressor is idle, pump 50 is adapted to force refrigerant from receiver 44 via pipe 48 to the evaporator. Conduits 45 and 48 extend through the tubular sections 34 and 35 which support casing 29 and are provided with flexible coils which permit vertical adjustment of the cooling-unit without disconnection from the refrigerant conduits 48 and 45. A thermostatically controlled valve generally designated 60 is included in a by-pass conduit 61 between suction-conduit 45 and high pressure conduit 40 for controlling the by-pass of refrigerant around the compressor, from the evaporator to the condenser coils 21. When valve 60 is closed, the compressor will draw refrigerant from the evaporator and under pressure force it via conduit 40 into the condenser-coils 21. When valve 60 is open and the compressor is idle, the refrigerant can by-pass the compressor and flow from evaporator 26 via header 46, conduit 45, conduit 61 in which valve 60 is included, conduit 40 and header 41 into the coils of condenser 21. When valve 60 is closed and valve 58 is open, the compressor can circulate refrigerant from the outlet header 46 of evaporator 26 via conduit 45, the compressor of unit 20, conduit 40, header 41, the coils of condenser 21, header 42 and conduit 43 to the receiver 44. Pump 50 will be operative to circulate the refrigerant

from receiver 44 and conduit 51 through the coil of evaporator 26 via conduit 48 and expansion valve 49, and also to force some of the refrigerant from the receiver 44 via conduit 59 and header 41 to exert pressure on the refrigerant in the condenser-coil.

Fig. 2 diagrammatically illustrates the circuits and switches; for normally closing valve 60 and permitting refrigerant to circulate from the evaporator via conduit 45, the compressor and conduit 41, to condenser 21; for opening valve 60 to permit the pump 50 to circulate the refrigerant (valve 58 being closed) from condenser 21, via conduit 43, receiver 44, conduit 51, pump 50, conduit 48, evaporator 26, conduits 45 and 61, valve 60 (then open), conduit 40, to condenser 21 and conduit 43 which communicates with the receiver; for closing valve 58 when the by-pass valve 60 is open, and opening valve 58 (valve 60 being closed) to cause pump 50 to boost the pressure on the refrigerant in conduit 59 and the condenser. The valve 58 includes a solenoid magnet 71 with a normally open valve member 72. The valve 60 includes a solenoid magnet 76 and a normally closed member 77. The magnets 71 and 76 are connected in series to a switch 73 controlled by a thermostat 75 responsive to outside temperature. Switch 73 is connected to line-conductors 78 and 79. The motor of the compressor-unit is controlled by a thermostat 82 responsive to outside temperature. Additionally said motor may also be thermostatically controlled, as well understood in the art, for automatically starting and stopping the compressor responsive to the temperature of the air cooled by the evaporator. When thermostat 75 closes switch 73, magnet 71 will be energized to close valve-member 72 and magnet 76 will be energized to open valve-member 77. When the magnets 71 and 76 are all deenergized, valve-member 72 of valve 58 will be open and member 77 of valve 60 will be closed.

The operation will be as follows: the apparatus may be designed to produce a head-pressure in the condenser of 30 to 60 lbs. p.s.i. while the temperature of the outside air around the condenser remains above 35° F. and the circulation of the refrigerant between the evaporator and the condenser by the compressor to maintain the desired range of cooling around the evaporator, in response to usual automatic thermostatic control for the compressor unit (not shown). Under these conditions, thermostat 82 which responds to the temperature of outside air will close its associated switch and keep the compressor-motor in operation. Thermostat 75, also responsive to the temperature of the outside air, will interrupt the circuit through solenoid magnets 71 and 76 so that valve 72 will remain open and valve 77 will remain closed. The refrigerant will then be circulated as follows: from the pressure side of the compressor of unit 20; conduit 40; inlet header 41 of condenser 21; conduit 43; receiver 44; conduit 51; pump 50; conduit 48; expansion valve 59; header 47, the coils and header 46 of evaporator 26; and conduits 46 and 47, to the suction side of said compressor. The refrigerant will be condensed when it passes into receiver 44 and a head-pressure of the refrigerant in the condenser will be maintained between 30 to 60 lbs. p.s.i. in the condenser and the refrigerant will be circulated to cool the evaporator as desired. The refrigerant in the condenser will be under head-pressure to circulate in the system and cool the inside air of normal temperature impelled through inside casing 29. Refrigerant from the outlet of pump 50 will also pass through valve 58, which is open, and conduit 59, to merge at conduit 40 with the refrigerant passing to the condenser from the compressor, to boost the pressure of the refrigerant in the condenser. This acts against the head-pressure of the refrigerant in the condenser which may at times be as high as 150 lbs. p.s.i. and relieves or reduces the load on the motor of the compressor-

unit. This results in economical operation of the compressor-motor.

If the temperature of the outside air impelled through casing 24 and condenser 21 drops to sub-normal, for example, to about or below 24° F., the pressure of the refrigerant in the condenser drops to 0 to 5 lbs. p.s.i. while the inside air around the evaporator may produce a pressure of 30 to 40 lbs. p.s.i. in the evaporator. These differentials in pressure will then cause the refrigerant from the evaporator to remain or be sucked into the condenser so that the compressor will not cause the refrigerant to flow from the evaporator to the condenser. This impairs or prevents the evaporator from performing its cooling function as desired.

For maintaining flow of the refrigerant from the condenser to the evaporator upon this drop in head-pressure in the condenser as aforesaid, the thermostat 82 which is responsive to the temperature below, for example 35° F., will open the electric circuit for and stop the motor of the compressor unit, and thermostat 75 closes switch 73 for energizing the electro-magnet 71 to close valve 58 and energizes magnet 76 to open valve 60. Thermostats 82 and 75 may be actuated in response, for example, to an outside temperature of about 30° to 35° F. or before the resultant drop in pressure in the condenser is sufficient to cause the refrigerant to be retained in the condenser. Pump 50 will continue to circulate the refrigerant from the receiver 44 via conduits 51 and 48; the inlet header 47, coils and outlet header 46 of evaporator 26; conduit 45; valve 60; conduits 61 and 40; the inlet header 41, the coils and outlet header 42 of condenser 21 and conduit 43, to the receiver 44. As a result, the differential pressures in the condenser 21 and evaporator will not stop the circulation of refrigerant between the evaporator and the condenser. This will continue until the compressor is again started in response to an increase of the temperature of the outside air to its normal range. The invention is not to be understood as restricted to the details set forth, since these may be modified within the scope of the appended claims without departing from the spirit and scope of the invention.

Having thus described the invention what I claim as new and desire to secure by Letters Patent is:

1. The combination of refrigerating apparatus including a motor-driven compressor and an air cooled condenser-coil connected to receive refrigerant from the compressor and mounted outside of a building where it is subjected to outside air; apparatus mounted in and for cooling air inside of the building, including an evaporator connected to receive refrigerant from the condenser-coil and to the suction side of the compressor; temperature controlled means for by-passing the refrigerant from the evaporator around the compressor and to the condenser-coils; a pump for forcing condensed refrigerant to the evaporator; and a conduit for refrigerant from the pump to the condenser-coils.

2. The combination of refrigerating apparatus including a motor-driven compressor and an air-cooled condenser-coil connected to receive refrigerant from the compressor and mounted outside of a building where it is subjected to outside air; apparatus mounted in and for cooling air inside of the building, including an evaporator connected to receive refrigerant from the condenser-coil and to the suction side of the compressor; temperature controlled means for by-passing the refrigerant from the evaporator around the compressor and to the condenser-coils; and a pump for forcing condensed refrigerant to the evaporator; and thermostatically controlled means for forcing refrigerant from the pump to the condenser-coils.

3. The combination of refrigerating apparatus including a motor-driven compressor, an air-cooled condenser-coil mounted on the outside of a building where it is subjected to outside air and connected to receive refrigerant

ant from the compressor, a liquid-receiver connected to receive refrigerant from the condenser-coil; air-cooling apparatus mounted inside of the building and including an evaporator connected to the suction side of the compressor, a pump connected to force refrigerant from the receiver to the evaporator, a conduit for the flow of some of the refrigerant from the pump into the condenser-coil; a thermostatically controlled valve for controlling said conduit; and a conduit for by-passing refrigerant from the evaporator to the condenser and around the compressor.

4. The combination of refrigerating apparatus including a motor-driven compressor, an air-cooled condenser-coil mounted on the outside of a building where it is subjected to outside air and connected to receive refrigerant from the compressor, a liquid-receiver connected to receive refrigerant from the condenser-coil; air-cooling apparatus mounted inside of the building and including an evaporator connected to the suction side of the compressor, a pump connected to force refrigerant from the receiver to the evaporator, a conduit for the flow of some of the refrigerant from the pump into the condenser-coil; a thermostatically controlled valve for controlling said conduit; a conduit for by-passing refrigerant from the evaporator to the condenser and around the compressor; and thermostatically controlled means for controlling the by-pass.

5. The combination of a refrigerating unit comprising a motor-driven compressor, a condenser coil, a conduit for refrigerant from the pressure side of the compressor to the condenser coil, a motor-driven impeller for circulating air around said coil, and a casing disposed on the outside of a building, provided with openings for the flow of outside air therethrough and in which said condenser-coil, impeller and compressor are mounted and an air-cooling unit comprising an evaporator connected to the suction side of the compressor, a casing inside of the building enclosing the evaporator, provided with openings for the flow of inside air therethrough; a liquid receiver connected to receive refrigerant from the condenser coil; a pump connected to force refrigerant from the receiver to the evaporator; a conduit for delivering some of the refrigerant from the pump into the condenser-coil; a temperature-controlled valve for cutting off flow through said conduit; and a by-pass for refrigerant, around the compressor, from the evaporator to the condenser, provided with a temperature-controlled valve for controlling the by-pass.

6. The combination of a refrigerating unit comprising a motor-driven compressor, a condenser-coil, a conduit for refrigerant from the pressure side of the compressor to the condenser-coil, a motor-driven impeller for air around said coil, and a casing disposed on the outside of a building provided with openings for the flow of outside air therethrough and in which said condenser-coil, impeller and compressor are mounted, and an air-cooling unit comprising an evaporator connected to the suction side of the compressor, a motor-driven impeller

for air around the evaporator, a casing inside of the building enclosing the evaporator and last named impeller, provided with openings for the flow of inside air therethrough; a liquid receiver connected to receive refrigerant from the condenser coil; a pump connected to force refrigerant from the receiver to the evaporator; a conduit for delivering some of the refrigerant from the pump into the condenser coil; a temperature-controlled valve for cutting off flow through said conduit; and a by-pass for refrigerant around the compressor from the evaporator to the condenser, provided with a temperature controlled valve for controlling the by-pass.

7. The combination of refrigerating apparatus including a motor-driven compressor and an air cooled condenser-coil connected to receive refrigerant directly from the compressor and mounted outside of a building where it is subjected to outside air and temperature controlled means responsive to said outside air for controlling said compressor; apparatus mounted in and for cooling air inside of the building, including a receiver for the condensed refrigerant, an evaporator connected to receive refrigerant from the condenser-coil and to the suction side of the compressor; temperature controlled means for by-passing the refrigerant from the evaporator around the compressor and to the condenser; and a pump connected to force condensed refrigerant from the receiver to the evaporator and merge it with the refrigerant passing from the compressor to the condenser during the simultaneous operation of the compressor and pump for cumulating pressures of refrigerant from the pump and compressor in the condenser.

8. The combination of refrigerating apparatus including a motor-driven compressor, an air-cooled condenser-coil mounted on the outside of a building where it is subjected to outside air and temperature-controlled means responsive to said outside air for controlling said compressor and connected to receive refrigerant directly from the pressure side of the compressor, a liquid-receiver connected to receive refrigerant from the condenser-coil; air-cooling apparatus mounted inside of the building and including an evaporator connected to the suction side of the compressor; a pump connected to force refrigerant from the receiver to merge with the refrigerant from the compressor in the condenser coil and boosting the head-pressure when the compressor and pump are simultaneously operated, temperature-controlled means for controlling the flow of refrigerant from the pump to the condenser, and temperature-controlled means for bypassing refrigerant from the evaporator around the compressor to the condenser when the compressor is idle.
